EARTH BORING DRILL AND METHOD

Lester C. Black, Los Angeles, Calif.

Application September 5, 1933, Serial No. 688,120

10 Claims. (Cl. 255—71)

This invention relates generally to drills of the rotary type which are adapted particularly for the boring of earth wells, and to methods for utilizing the same.

It is an object of the invention to provide a drill of the above character which will afford a relatively high boring speed and relatively efficient drilling action.

10 Another object of the invention is to provide an improved form of rotary drill which can be used over relatively long periods of time without the necessity of servicing, and in which the cutters can be readily replaced in the event they become broken or worn.

15 Another object of the invention is to provide a rotary drill which will have a relatively wide range of application with respect to different formations, and which when used upon soft formations, will drill at a rapid rate without becoming clogged.

20 Further objects of the invention will appear from the following description in which the preferred embodiment of the invention has been set forth in detail in conjunction with the accompanying drawings.

25 Referring to the drawings:

Figure 1 is a side elevational view, partly in cross-section, illustrating a drill incorporating the present invention.

30 Fig. 2 is a cross sectional detail taken along the line 2—2 of Fig. 1.

Fig. 3 is a side elevational view illustrating collectively certain parts for the attachment of the cutters to their associated heads.

35 Fig. 4 is a cross sectional detail taken along the line 4—4 of Fig. 1.

Fig. 5 is a plan view illustrating a formation pattern at the bottom of the well, such as is produced by the drill illustrated in the drawings.

40 Fig. 6 is a diagrammatic view illustrating the manner in which the cutters are brought into action upon the formation being drilled.

Referring first to Figs. 1 and 2 of the drawings, the drill illustrated therein consists of a shank 10, the upper end of which is threaded as at 11 or otherwise formed to afford convenient coupling to the lower end of a hollow drill stem. Secured to the lower end of the shank 10 there is a head 12 to which a wobbling movement is imparted as will be presently explained, and carried by the head 12 are a plurality of cutters 13.

45 The particular form of connection illustrated between the shank and the head, is constructed as follows:—The lower portion 14 of the shank

10 is enlarged somewhat and offset from the general axis of rotation 16 of the shank. The lower end face 17 of the portion 14 is finished along a plane arranged at an angle to the axis 16, the angle as illustrated being about 22½ degrees. 5 Formed within the shank portion 14 there is a cylindrical counterbore 18, which serves to accommodate a stud 19 formed upon the head 12. To afford a minimum amount of resistance to turning movement between the head and the shank, and in order to lock the head against removal, the stud 19 is shown provided with annular grooves 21, which are aligned with grooves 22 formed in the side walls of counterbore 18. Fitted within these grooves are the ball bearings 15 23, which are adapted to be introduced into or removed from the grooves 21 and 22 thru side openings fitted with removable plugs 24 and 25. Separate thrust washers 27 and 28 are also preferably interposed between the lower face 20 17 of the shank, and the cooperating annular shoulder 29 formed upon the head 12. These thrust washers are preferably locked to shank 10 and to the head respectively, by means of keys 31 and 32. 25

The head 12, below the thrust shoulder 29, is formed to afford a plurality of divergent legs 33, and it is to these legs that the cutters 13 are rotatably secured. I prefer that the cutters be of the disc type. Such cutters are characterized by 30 peripheral cutting edges, and by the fact that they are advanced against the formation in a direction generally laterally with respect to planes normal to their axes of rotation. Each of the cutters as illustrated consists of a body 34 formed of a metal or metal alloy having suitable hardness and strength. The inner annular web portion 36 of this body cooperates with other elements to be presently explained, to form a suitable journal. The periphery of the body is 40 formed to afford an annular groove 37, which serves to provide two spaced circumferential cutting edges 38 and 39. As will be presently made clear, the use of two spaced cutting edges is not essential to the invention, but is desirable and of 45 considerable utility.

The particular form of connection illustrated between each of the cutters 13 and its associated leg 33, to form a suitable journal and to permit removal of the cutters for replacement and repair, incorporates the invention disclosed and claimed in my Patent No. 1,655,176. Briefly this arrangement is as follows:—Fitted upon the annular web 36 there is an arcuate bushing 41, the rear face of which is continued to form an 50

annular washer 42. The lower end of the associated leg 33, has an integral projecting portion 43 provided with an arcuate groove 44 to receive bushing 41, and is also provided with a set back 5 surface 46 in a plane coincident with the rear face of groove 44. Therefore when bushing 41 is within groove 44 as shown in Fig. 1, the washer 42 engages surface 46. Extending thru the leg 33, and somewhat eccentric with respect to the 10 axis of rotation of the cutter, there is a retaining bolt 47. This bolt passes thru an apertured lug 48, which is formed as a part of a crescent shaped retainer block 49. This block is provided with an arcuate recess 51 to accommodate web 36, 15 and thus serves to complete the journal for the cutter together with the bushing 41.

With respect to the positioning of the cutters 13 upon the head 12, in general the axes of rotation of the cutters should be inclined with respect to the axis of rotation of the head relative to the shank 10, rather than at right angles or parallel thereto. With the arrangement illustrated the general plane of each of the cutters, that is a plane taken normal to the axis of rotation of a cutter and medial of the body thereof, extends in a general direction outwardly from the axis of rotation of the head with respect to the shank, and at an angle thereto. That is, each cutter has a portion of its periphery extending downwardly toward the bottom of the well and another portion of its periphery extending inwardly toward the axis of the head, so that each of the cutters has one of its side faces presented toward the direction of rotation of the head or drill. With the particular arrangement illustrated, which gives good results, the aforesaid general plane of each of the cutters 13 is at an angle of about $22\frac{1}{2}$ degrees with respect to the axis of rotation of the head about the shank.

40 In operating a drill of the type described above, it is desirable to circulate a suitable fluid medium, such as the usual rotary drilling mud, downwardly thru the drill stem, to be discharged in a region adjacent the cutters 13. For this purpose the head 12 is shown provided with a central opening to accommodate a nipple or pipe fitting 52. The upper end of this fitting is attached to the shank, and is in communication with a passage 53 thru which mud can be forced from the drill stem. The lower end of pipe fitting 52 terminates in a region generally surrounded by the cutters 13.

Before describing the manner in which my drill operates in practice, certain additional inherent 55 characteristics may be pointed out. Assuming that the cutters have a positioning with respect to the head 12, and that the head 12 likewise has a positioning with respect to the shank, as specifically referred to above, with respect to an 60 imaginary plane 54 the general planes of the cutters assume a definite angle of $22\frac{1}{2}$ °. It will be noted that this plane 54 is taken normal to the axis of rotation of the head about the shank. With respect to a horizontal plane 56, the general 65 planes of the cutters assume various angles from a vertical position to an angle of maximum inclination, which in the aforesaid specific example is 45°. If the head 12 is restrained against rotary movement, but otherwise permitted to move freely, and shank 10 is rotated about the axis 16, it is evident that a nutatory or wobbling movement will be imparted to the head and to the cutters. If finite restraints are placed upon 70 movements of the cutters, both with respect to rotary movement about axis 16, and nutatory

movements, (as in drilling operations) a torque component is impressed upon head 12, tending to rotate the head and cutters in the same direction of rotation as that of the shank 10. In this connection it should be noted that during drilling operations the shank 10 (except for normal advancing and retracting movements) cannot readily move up and down in synchronism with nutatory movements of the head, because it is connected to the lower end of a relatively heavy 10 drill stem.

Assuming now that the drill is operating in a well with the cutters 13 against a bottom formation, and that the shank 10 is being continuously rotated about the general vertical axis of the well, the restraints placed upon the cutters by virtue of contact with the formation, which restraints tend to oppose both rotary movements of the cutters about the vertical well axis and nutatory movements, the result is that head 12 is caused to 20 rotate continuously at a speed substantially less than the rate of rotation of the shank, and that nutatory movement of the head takes place to repeatedly impact the cutters upon the formation. In other words the head together with the cutters is caused to continuously wobble upon the formation and this wobbling movement occurs together with rotational movement about the general vertical axis of the well. At the same time, because of the setting of the disc type cutters 25 with respect to the axis of rotation of the head about the shank, the cutters also revolve about their individual axes with respect to the head, so that fresh cutting surfaces are being continuously brought into contact with the formation. 30

Better understanding of the action described above can be had by reference to Figs. 5 and 6. Fig. 5 represents a typical formation pattern on the bottom of the well during operation of my drill. It will be noted that this pattern is not 40 that of a torroid having its axis in a horizontal plane, but that valleys or pockets are formed separated by ridges. Thus in this case two similar pockets or valleys 1 are formed, which are separated by the central ridge 2. The arrow in this 45 figure indicates the direction of rotation of the shank with respect to the pattern being formed. Taking now a cross section along an imaginary cylinder 3, we have the development of Fig. 6, in which the action of the cutters upon the formation is also illustrated. The angle of attack 50 of the cutters upon the formation for the up-slopes *a* varies from a position in which both cutting edges are brought into contact with the formation, to a vertical position about half way up the slope, and to a position of substantially one-half maximum inclination (e.g. $22\frac{1}{2}$ °) at the top of the slope. For the down slopes *b*, the inclination varies from half maximum value at the top of the slope, to maximum inclination value 60 about half way down the slope, and then back to approximately one-half maximum inclination at the bottom of the down slope.

With a tool having three cutters substantially as illustrated in the drawings, it has been found 65 that the ratio of rotation between the shank and the head 12, is about 3 to 1, that is, the head is rotated one time for about three complete revolutions of the shank. Therefore for each complete revolution of the shank, each cutter because 70 of the nutatory or wobbling action imparted to it, makes three distinct rises and three plunges. Since for one complete revolution of the shank, the head progresses only one-third revolution, it 75 is evident that each cutter does not bear con-

tinuously upon the formation to produce a pattern such as illustrated in Figs. 5 and 6, but that the cutters act successively upon the formation, so that each cutter for only a part of its rise and 5 plunge cycle is brought into contact with the formation. However cutting is not confined to a period when a cutter is plunged downwardly, but as indicated in Fig. 6, cutting may also occur during a rise.

- 10 The particular pattern produced upon the formation being drilled will of course vary in accordance with the particular design of drill utilized, and may also vary somewhat in accordance with the character of the formation acted upon.
- 15 For example with a drill utilizing four cutters in place of three, it has been found that three valleys are produced separated by three ridges, and there will be a higher ratio between the speed of rotation of the shank and that of the head. In 20 other words the number of valleys produced in the formation pattern is one less than the number of cutters employed.

It is of course possible to vary the construction and design of the cutters, as for example to employ disc cutters provided with a single circumferential cutting edge or row of cutting teeth. However the use of two cutting edges such as illustrated, spaced apart in the direction of the axis of rotation of the cutter, is desirable for a reason 25 which is evident from an inspection of Fig. 6. During operation of a cutter upon the formation, both of its cutting edges are contacted with the formation simultaneously for only an instant. During other periods the cutting edges are in 30 action separately, so that wear is distributed substantially equally between them. Such action makes for better penetration into the formation and more efficient cutting action, it extends the useful life of the cutter, and it makes possible a maximum amount of cutting surface with a minimum 35 number of cutters, thus affording a maximum speed ratio between the shank and the head.

It is also evident that I may deviate somewhat 40 from other structural details of the drill illustrated in the drawings. Thus although the particular angular positioning of the head with respect to the shank, and of the cutters with respect to the head, appear to be desirable as 45 specified by way of example, deviations therefrom within the spirit of the invention are deemed feasible or may even be desirable dependent upon the conditions encountered.

I claim:

- 55 1. In a drill for boring wells, a shank adapted to rotate about the general vertical axis of the well, a head adjacent the lower end of the shank, said head being mounted upon said shank for rotation about an axis at an angle to the axis of said shank, and a plurality of circumferentially spaced cutters of the disc type rotatably mounted upon said head, each of said cutters having one of its side faces presented toward the direction of rotation of said head.
- 60 2. In a drill for boring wells, a shank adapted to rotate about the general vertical axis of the well, a head adjacent the lower end of the shank, said head being mounted upon said shank for rotation about an axis at an angle to the axis of said shank, and a plurality of circumferentially spaced cutters of the disc type rotatably mounted upon said head, each of said cutters being positioned to have a portion of its periphery extending 65 downwardly toward the bottom of the well and another portion of its periphery extending

inwardly toward the axis of said head, whereby each of said cutters has one of its side faces toward the direction of rotation of said head.

3. In a drill for boring wells, a shank adapted to rotate about the general vertical axis of the well, a head adjacent the lower end of the shank, said head being mounted upon said shank for rotation about an axis at an angle to the axis of said shank, and a plurality of circumferentially spaced cutters of the disc type rotatably mounted upon said head, the central plane of each cutter making an acute angle with a plane through the axis of the head and passing through said cutter.

10 4. In a drill for boring wells, a shank adapted to rotate about the general vertical axis of the well, a head adjacent the lower end of the shank, said head being mounted upon said shank for rotation about an axis at an angle to the axis of said shank, and a plurality of circumferentially spaced cutters of the disc type rotatably mounted upon said head, the central plane of each cutter being substantially parallel to the axis of said shank at one point during the rotation of said head.

15 5. In a drill for boring wells, a shank adapted to rotate about the general vertical axis of the well, a head adjacent the lower end of the shank, said head being mounted upon said shank for rotation about an axis at an angle to the axis of said shank, and a plurality of circumferentially spaced cutters 20 of the disc type rotatably mounted upon said head, the axis of each cutter being substantially tangential, at one point during the rotation of the head, to a circle concentric to the axis of the shank.

25 6. In a rotary drill for boring earth wells, a plurality of disc cutters carried by said drill and circumferentially spaced from each other, said disc cutters being independently rotatable and mounted upon said drill so as to present a side 30 face toward the direction of rotation of the drill, the axis of each cutter being substantially tangential, at one point during the rotation of the head, to a circle concentric to the axis of the shank.

35 7. In a rotary drill for boring earth wells, a plurality of disc cutters carried by said drill and circumferentially spaced from each other, said disc cutters being independently rotatable and mounted upon said drill so as to present a side 40 face toward the direction of rotation of the drill, and means for causing said cutters to progress about the axis of the well with rising and plunging movements.

45 8. In a rotary drill for boring earth wells, a plurality of disc cutters carried by said drill and circumferentially spaced from each other, said disc cutters being independently rotatable and mounted upon said drill so as to present a side 50 face toward the direction of rotation of the drill, and means for causing said cutters to progress about the axis of the well with rising and plunging movements and for causing the edges of said cutters to engage the formation being cut at varying angles.

55 9. In a rotary drill for boring earth wells, a plurality of disc cutters carried by said drill and circumferentially spaced from each other, said disc cutters being independently rotatable and mounted upon said drill so as to present a side face 60 toward the direction of rotation of the drill, and means for causing said cutters to progress about the axis of the well with rising and plunging movements and for causing the edges of said cutters to engage the formation being cut at varying angles.

65 10. In a rotary drill for boring earth wells, a plurality of disc cutters carried by said drill and circumferentially spaced from each other, said disc cutters being independently rotatable and mounted upon said drill so as to present a side face 70 toward the direction of rotation of the drill, and means for causing said cutters to progress about the axis of the well with rising and plunging movements and for causing the edges of said cutters to engage the formation being cut at varying angles.

the axis of the well with rising and plunging movements, said disc cutters each having a plurality of spaced peripheral cutting edges.

10. In a rotary drill for boring earth wells, a plurality of disc cutters carried by said drill and circumferentially spaced from each other, said disc cutters being independently rotatable and mounted upon said drill so as to present a side

face toward the direction of rotation of the drill, and means for causing said cutters to progress about the axis of the well with rising and plunging movements and for causing the edges of said cutters to engage the formation being cut at varying angles, said disc cutters each having a plurality of spaced peripheral cutting edges.

LESTER C. BLACK.
